COMBINED CLIP AND SPOON HOLDER FOR A
JAR OR THE LIKE

Theodore Bush, Muncie, Ind.

Filed Aug. 14, 1959, Ser. No. 57,183

Term of patent 14 years

(Cl. D58—26)

FIG. 1

FIG. 2

FIG. 3

FIG. 5

Fig. 1 is a top plan view of a combined clip and spoon holder for a jar or the like embodying my new design; Fig. 2 is a front elevational view thereof; Fig. 3 is a side elevational view thereof; Fig. 4 is a bottom plan view; and Fig. 5 is a rear elevational view thereof. The side not shown is substantially like the side shown in Fig. 3.

I claim:

The ornamental design for a combined clip and spoon holder for a jar or the like, as shown and described.
